CLAIM

I claim the ornamental design for a precision rifle case, as shown and described.

DESCRIPTION

FIG. 1 is an isometric view of a precision rifle case showing my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawing illustrate portions of the precision rifle case, including stitching, and form no part of the claimed design.

The claimed precision rifle case can be used to store a precision rifle and shooting accessories.

The "Savior Equipment" logo forming part of the disclosure is a registered trademark of Eosen, Inc.
